METHOD OF FREEING AND EJECTING DIE
CASTINGS FORMED ON CORES

Otto Gries, New Rochelle, and Louis H. Morin, Bronx, N. Y.; said Gries assignor of one-half to Crown Fastener Corporation, Warren, R. I., a corporation of Delaware

Application August 1, 1947, Serial No. 765,330

5 Claims. (Cl. 18—55)

1

This invention relates to the formation of die castings on core pins or members disposed between and entering the cavity of a pair of dies. More particularly, the invention deals with a method of first freeing the core pin from the casting, thus using the core pin to eject the casting from the die cavities and then to finally strip the casting from the core pin.

The novel features of the invention will be best understood from the following description when taken together with the accompanying drawings, in which certain embodiments of the invention are disclosed, and in which the separate parts are designated by suitable reference characters in each of the views, and in which:

Fig. 1 is a diagrammatic sectional view illustrating the formation of a casting on a core pin and illustrating means for removal of the casting from the pin.

Fig. 2 is a sectional view through the dies and part of the core pin structure, the section being on the line 2—2 of Fig. 1 and indicating the dies in open position in dot-dash lines.

Fig. 3 is a view similar to Fig. 1 showing the casting in section and illustrating the first step in freeing the casting on the core pin.

Fig. 4 is a view similar to Fig. 3 showing the step of ejecting the casting from the core pin.

Fig. 5 is a view similar to Fig. 1 showing a modified method of procedure.

Fig. 6 is a view similar to Fig. 5 showing the step of freeing the core pin in the casting.

Fig. 7 is a view similar to Fig. 6 showing the step of stripping the casting from the core pin.

Fig. 8 is a view similar to Figs. 1 and 5, showing another form of construction for actuating the core pin.

Fig. 9 is a view similar to Fig. 8 showing only a part of the construction, with parts in a different position; and

Fig. 10 is a view similar to Fig. 9 showing the operation of removing the casting from the die and stripping the casting from the core.

In Figs. 1 to 4 inclusive, we have diagrammatically illustrated one method of procedure in freeing a casting on a core pin, ejecting the casting from the dies and stripping the casting from the core pin. In Figs. 1, 3 and 4, we have indicated at 11, one die of a pair of relatively movable dies, the companion die being shown at 11' in Fig. 2 of the drawing. In illustrating one adaptation of the invention, we have shown the dies as having a cavity 12 for the formation of a winged nut 13, the nut having a central tubular portion 14, the bore 15 of which, note

2

Fig. 3, is formed by a reduced end 16 of a core pin 17. The pin 17 is arranged in a tubular portion 17' of the dies.

At 18 is shown an injection nozzle for injecting casting material into the cavity 12 through a gate passage 19, in a manner well known in the art. This forms on the resulting casting, a gate part 20, which is removed in any suitable manner.

10 Supported over the dies is a U-shaped bracket 21, one part 22 of which has an aperture 23 to guide the pin 17, the other part 24 has a large aperture 25 to clear the pin 17 as well as a sleeve 26 slidably mounted on the pin. The sleeve 26 forms a casting stripper element, as will later appear. The upper surface of the part 24 forms a stop shelf 27 against which a collar 28 fixed on the pin 17 rests in properly positioning the end 16 of the pin within the die cavity 12. Suitable 20 means of adjustment can be provided for this purpose. Mounted on the pin 17 between the part 22 of the bracket and the collar 28 is a spring 29 which normally supports the collar in engagement with the shelf or stop 27.

25 The sleeve 26 has centrally thereof a pair of circumferential collars, as at 30, forming an annular recess 31 therebetween. Swingably mounted on a shaft or rod 32 is a lever 33, the forked end 34 of which includes pins, as indicated at 35, which operate in the annular recess 31 in movement of the sleeve 26 longitudinally of the pin 17.

The method of procedure in freeing, ejecting and stripping a casting will be as follows:

35 In Fig. 1 is shown the position of the parts as and when a casting 13 is formed on the end 16 of the core pin 17. Immediately upon completion of the formation of the casting, the lever 33 is swung upwardly by any suitable means to 40 raise the sleeve 26 into the position shown in Fig. 3, in which operation the sleeve engages the collar 28 and thus moves the core pin 17 vertically against the action of the spring 29 and this frees the end 16 in the casting 13. In the chilling of the casting, as is the usual practice, there is a tendency for the casting to shrink upon a pin, and the upward movement referred to above, frees the pin end 16 against the shrinking action.

50 The above operation is performed while the dies are still in closed position, and the upward movement is sufficient to provide the freeing action while at the same time, leaving the end 16 of the pin still frictionally disposed within the bore 15 of the casting 13. The next step in

the operation is to separate the dies, moving the same into the dot-dash position shown in Fig. 2. In this operation the casting is automatically ejected from the die cavities and remains supported on the end 16 of the pin 17. In the next operation, the lever 33 moves downwardly, bringing the sleeve 26 from the position shown in Fig. 3 to the position shown in Fig. 4, in which latter position the lower end of the sleeve 26 has moved beyond the end limits of the end 16 of the core pin, thus stripping the casting 13 from the core pin and allowing it to drop into a suitable receptacle, not shown. The ejected or released or stripped casting is shown below the dies in Fig. 4 of the drawing. After completing the operation in Fig. 4, the lever 33 is again moved into the position shown in Fig. 1 to clear the dies, the core pin 17 is now supported upon the shelf 27, the dies are again closed, and the next successive casting is made.

By proceeding in the manner outlined above, which method is substantially carried out in conjunction with the other forms of construction shown, it is possible to produce die castings at a high rate of speed, in that a minimum amount of motion takes place within each cycle of operation of the machine and by contributing only two motions to the dies or die, namely one opening movement and one closing movement.

In Figs. 5 to 7 inclusive, we have shown a slight modification of the method of procedure shown in Figs. 1 to 4. The dies or die 11 are the same as that shown in Figs. 1 to 4, the casting 13 is the same, as is also the ejector nozzle 18. In Figs. 5 to 7 inclusive, we have shown at 36 a core pin having a reduced end 37 similar to the end 16. The pin 36 is slidably mounted in an elongated aperture 38 of a bracket 39 and swingably mounted in the bracket 39 is a lever 40 generally similar to the lever 33 and having a forked end 41 operating upon a pulley-like sleeve 42 secured upon the upper reduced end 43 of the pin 36 by means of a nut 44. The sleeve 42 normally seats upon a stop shelf 45 at the upper end of the bracket 39 in properly positioning the end 37 of the core pin within the cavity 12 of the die.

With this construction, after the casting has been formed, and while the dies are still in closed position, the pin 36 is first moved upwardly by the lever 40 as indicated in Fig. 6 of the drawing to free the end 37 in the casting 13, then the dies are separated and the casting 13 is ejected from the cavity 12 whereupon the lever 40 is again moved in an upward direction which raises the pin 36 within the aperture 38 so as to strip the casting 13 from the pin by engagement with the lower end 46 of the bracket 39, the result of which operation is shown in Fig. 7 of the drawing where the casting 13 is shown below the die 11.

From the foregoing, it will be apparent that in the method of procedure shown in Figs. 5 to 7 inclusive, the one lever 40 is employed and this lever is given two upward motions for freeing and then stripping the casting, the first motion being slight, bringing the lever to a stop position as shown in Fig. 6, whereupon the upward motion is continued and after the casting has been removed or stripped from the core pin, the lever 40 is then swung down into the position shown in Fig. 5, the dies are again closed and the cycle of operation is again repeated.

In Figs. 8 to 10 inclusive is shown another method of procedure. In these figures, a stationary die 47 and a movable die 48 are employed, the die 48 being slidable in a suitable guide and

support 49 and actuated by any suitable means, as indicated at 50. The die 47 is fixed in any suitable manner and includes a bracket portion 51 which in conjunction with the guide and support 49 forms guides and supports for a slide 52, as will clearly appear in Fig. 8 of the drawing. Suitable means 53 is provided for actuating the slide in the manner later described. The dies have a cavity 12' similar to the cavity 12 for forming a winged nut 13' similar to the winged nut 13.

At 17' is shown a core pin similar to the pin 17 and having a reduced end 16' similar to the end 16. On the pin 17' is arranged a sleeve 26' similar to the sleeve 26, the pin 17' also having a collar 28' similar to the collar 28. At 33' is shown a lever similar to the lever 33 for operating the sleeve 26'. In Fig. 8, an actuating lever 54 is also indicated as extending through an elongated aperture 55 in the slide 52 and at 56 is shown a rod or link for actuating the lever 54.

The slide 52 around the pin 17' and beneath the collar 28' has a stop platform or shelf 27' similar to the shelf 27 in alignment of the end 16' of the core pin in the cavity 12'. At 29' is shown a spring similar to the spring 29 and at 57 is shown an arm similar to the bracket end 22, apertured as seen at 58, to guide the pin 17'.

The slide 52 includes downwardly extending members 59 in which is supported the pin or shaft 60 to which the levers 33' and 54 are secured so that the levers operate as a unit with the slide 52.

The primary difference in the method of procedure shown in Figs. 8 to 10 inclusive over that illustrated in Figs. 1 to 4 inclusive, resides in the use of a fixed die and a movable die, thus requiring an additional movement to the core pin over that illustrated in Figs. 1 to 4 inclusive. In other words, after the casting has been formed in the cavity 12' with the dies in the position shown in Fig. 8, the lever 33' is first actuated to raise the pin in freeing the end 16' in the casting 13' and this is accomplished with the die 48 in the closed position.

Upon completing this operation, the die 48 is then moved into open position as indicated in Fig. 9, whereupon the slide 52 is operated to move the core pin 17' from the position shown in Fig. 9 to that shown in Fig. 10, thus ejecting the casting from the fixed die 47 and bringing the casting in position to be stripped from the core pin. The levers 33' and 54 are now operated to move the sleeve 26' downwardly on the core pin stripping the casting therefrom the same as in Fig. 4 of the drawing. After completing this operation, the sleeve 26' is raised, the slide 52 is then moved to the right, as seen in Fig. 8, returning the core pin 17' to position within the cavity of the fixed die 47. In the above operation the die 48 can be moving into its closed position. This returns the die to the position shown in Fig. 8, whereupon the next successive casting can be formed and then the next cycle of operation is repeated.

In order to simplify the present diagrammatic illustrations, we have shown the formation of a single type and kind of casting in the several views. It will be understood, however, that castings of any desired shape or contour can be formed, particularly where core pins are employed in the production of the casting, or where a core pin is utilized as a means for ejecting a casting from the cavities of the dies and as a

means for supporting the casting in the stripping operation.

It will be apparent that the sleeve members 26—26' as well as that part of the bracket 39 disposed upon the pin 36 constitute strippers or stripper members for stripping the casting from the pin or core member. In this connection it will be understood that with the structure shown in Figs. 1 to 4 and 8 to 10 inclusive, the core or pin member is automatically returned to alined position with respect to the cavities by the springs 29—29' during the stripping operation so that the pin or core member is in position to be engaged by the dies when the dies are closed. It will further be apparent that when the dies are separated, as in Figs. 4 and 7 inclusive, or when the pin member is moved into position spaced with respect to both dies, as indicated in Fig. 10, the pin or core member is arranged in what may be termed a stripper station, leaving the casting free for discharge into a suitable receptacle when the same is stripped from the pin or core member.

Having fully described our invention, what we claim as new and desire to secure by Letters Patent is:

1. The method of forming, ejecting and discharging die castings, which comprises forming a die casting on a pin member supported within the cavities of a pair of relatively movable dies, moving the pin member relatively to the casting while supported in the dies to free the casting from seizure on said pin member, moving the dies out of contact with each other and also out of contact with the pin member and the casting, and then stripping the casting from the pin member by a stripper mounted on and movable longitudinally of said pin member.

2. The method of forming a die cast body about a core member in a pair of dies and then discharging the body from said dies and member which comprises: casting said body about the core member while the latter is positioned in a die cavity formed by the closed dies, moving the member partially away from the body while the dies are still closed to partially break the grip of the die cast body thereon, opening the dies, moving the member with the body supported thereon back to the original position of said member, stripping the body from the core member, and closing the dies about the stripped member preparatory to casting another body thereon.

3. The method of forming a die cast body about a core pin in a pair of dies and then discharging the body from the dies and core pin which comprises first forming the casting on

the core pin supported within the cavities of the closed dies, then moving the core pin relatively to the casting with the dies retained in closed position to free the casting against seizure on the pin, then moving one die into open position, then moving the core pin with the casting thereon away from the other die to eject the casting from the last named die and to move the core pin into stripping position, and then stripping the casting from the core pin by a stripper member arranged upon the core pin by moving the member and core pin one relatively to the other in the stripping operation.

4. The method of forming, ejecting and discharging die castings, which comprises forming a die casting on a pin member supported within the cavities of a pair of closed dies one of which is fixed, then while the dies are in their original closed position moving the pin member partially out of the casting in order to free the casting from seizure on the pin member, separating the dies by movement of one die away from the fixed die, supporting the casting in the cavity of the fixed die by said pin, then moving the pin and casting out of the fixed die to a stripper station spaced with respect to both dies, and stripping the casting from the pin member by means of a stripper movably arranged on said pin member.

5. The method of forming a die cast body about a core pin in a pair of dies and then discharging the body from the dies and core pin which comprises first forming the casting on the core pin supported within the cavities of the closed dies, then moving the core pin relatively to the casting with the dies retained in their original closed position to free the casting against seizure on the pin, then separating the dies and ejecting the casting therefrom so that the latter is entirely out of contact with the dies, said casting being still attached to the pin, then stripping the casting from the core pin, and then closing the dies around the core pin preparatory to forming the next successive casting.

OTTO GRIES.
